(57) **CLAIM**

The ornamental design for a handheld controller, as shown and described.

DESCRIPTION

FIG. 1 is a perspective view of the handheld controller showing my new design;

FIG. 2 is a top plan view thereof;

FIG. 3 is a bottom plan view thereof

FIG. 4 is a front elevation view thereof;

FIG. 5 is a rear elevation view thereof;

FIG. 6 is a right side elevation view thereof; and,

FIG. 7 is a left side elevation view thereof.

The broken lines shown are included for the purpose of illustrating portions of the handheld controller that form no part of the claim.
